UNITED STATES PATENT OFFICE

ROBERT GEORGE, OF PARIS, FRANCE, ASSIGNOR TO CHENEY BROTHERS, OF NEW YORK,
N. Y., A CORPORATION OF CONNECTICUT

DESIGN FOR A TEXTILE FABRIC

Application filed September 28, 1932. Serial No. 45,117. Term of patent 3½ years.

To all whom it may concern:

Be it known that I, ROBERT GEORGE, a citizen of Switzerland, residing at 14, Rue due 4-Septembre, Paris, in the Republic of France, have invented a new, original, and ornamental Design for Textile Fabrics, of which the following is a specification, reference being had to the accompanying drawing, forming part thereof.

The figure is a plan view of a textile fabric, showing my new design. The area with-

in the dot and dash lines shows one complete unit of the design. The repeats are arranged in vertical rows, and adjacent vertical rows are one half a complete unit offset so that the angle of the complete unit indicated by letter A corresponds with the angle B of one of the repeats in an adjacent vertical row.

I claim:

The ornamental design for a textile fabric, substantially as shown and described.

ROBERT GEORGE
